(57) **CLAIM**

The ornamental design for a modular wall planter, as shown and described.

DESCRIPTION

FIG. 1 is a perspective view of a modular wall planter showing my new design;

FIG. 2 is a front elevation view of the modular wall planter; FIG. 3 is a rear elevation view of the modular wall planter; FIG. 4 is left side elevation view of the modular wall planter; FIG. 5 is a right side elevation view of the modular wall planter;

FIG. 6 is a top plan view of the modular wall planter; FIG. 7 is a bottom plan view of the modular wall planter; FIG. 8 is a perspective view of the modular wall planter with environment; and,

FIG. 9 is a perspective view of the modular wall planter with environment.

The broken lines showing planters and the broken lines showing a wall are for the purpose of illustrating environmental structure and form no part of the claimed design. The broken lines showing portions of the modular wall planter form no part of the claimed design.

1 Claim, 9 Drawing Sheets
